ELECTRICAL DIFFERENTIAL OIL WELL DRILLING SYSTEM

Stephen A. Staeg, Pittsburgh, Pa., assignor to Westinghouse Electric & Manufacturing Company, East Pittsburgh, Pa., a corporation of Pennsylvania

Application January 6, 1933, Serial No. 650,401

8 Claims. (Cl. 255—19)

My invention relates to rotary well drilling systems.

I am well apprised of the fact that various attempts have heretofore been made to control the hoisting motor of a rotary well drilling system as a function of the load variations on the motor driving the drill table as different types of earth strata are encountered. However, in previous devices the flexibility of the control fell short of expectations, and further the amount of equipment needed made the price of the installations prohibitive to the trade.

In working on the invention herein presented, I kept the prior art in mind, and one of the objects of my invention is the provision of a simple, practical, inexpensive and accurate system of control whereby the drilling motor cannot be overloaded, crooked holes are avoided, broken and twisted-off drill stems are prevented, and the drilling operation proceeds with the maximum speed at which a given formation can be properly drilled.

It is also an object of my invention to limit both the torque on the drill motor and the weight of the drill stem.

A further object of my invention is the provision of a control system where the hoist motor need only be of a capacity sufficient to retrieve the drill stem during drilling at such a speed that a constant torque is maintained on the drill motor.

A still further object of my invention is to control the movement of the drill stem as a function of the speed of the drill motor.

Other objects and advantages will become apparent from a study of the following specification when considered in conjunction with the accompanying drawing, in which the single figure is a diagrammatic illustration of my control system as applied to a rotary drilling equipment.

Referring more particularly to the drawing, it will be apparent that I propose to use a wound rotor induction motor 11 for driving the drill table 1. The drill table is operatively secured to the drill stem 2 which operates in the well 3. Since the drilling equipment is a conventional rotary type, it is provided with a water supply pipe 4 for removing the drilling material at the bottom of the well and the stem is suitably supported by the link 5 and hook 6 through cable 7 from the crown block 8. The cable 7 is secured at some fixed point 9 to the derrick and the other end of the cable is wound about the hoist drum 10.

The hoist drum 10 is arranged to be operated by a direct-current torque motor 12 which is directly connected in the armature circuit of a di-

rect-current generator 13 mounted on the shaft of an induction motor 14. A separate exciter 16 is provided for exciting itself and the generator and the motor 12. It will be apparent that the machines 13 and 14 are nothing more than a 5 motor generator set for supplying energy to the torque motor 12, the motor 14 being secured through suitable switches SW to the source of alternating current 15.

To properly control the torque of motor 12 the 10 excitation of the generator 13 is varied as a function of the current drawn from the line by the wound rotor induction motor 11 and as a consequence, the weight of the drill stem supported on the bottom of the well is maintained substantially constant in a manner described more in detail hereinafter.

Probably a better understanding of my invention can be had by studying a sequence of operation for starting the drilling equipment and for 20 normal drilling.

Assuming conductors 15, representing the source of alternating-current power, are suitably energized, the motor 14 will thus operate, driving the generator 13 and the exciter 16. Since the 25 circuit for the wound rotor induction motor is still open at the contact members 33, 34 and 35, the field winding 30 of the generator 13 is not energized and the generator 13 supplies energy of relatively small voltage to the motor 12. The 30 motor 12 tends to hoist the drill stem 2 from the well by a torque which is determined by the voltage of the generator 13 and excitation of the field 35 25 of the motor 12.

Since the exciter 16 is operating, the buses 19 35 and 20 are energized and the exciter field 17 is thus suitably self-excited through rheostat 18. Further, the generator 13 is excited to a predetermined degree by the field winding 21 through rheostat 22. The motor 12 has its field winding 40 25 also excited through conductor 23, rheostat 24, resistor 26, to the bus 19. If now the controller 32 be moved in the direction indicated by the arrow to the first controller position *a*, contact members 33, 34 and 35 are bridged by the 45 controller segments 36, 37 and 38, respectively, thereby energizing the primary winding 43 of the motor 11 through conductors 40, 41 and 42. For the first controller position all of the resistors 44, 45 and 46 are in the secondary circuit 50 of the motor 11 and in consequence, a large starting torque is provided for the drill motor. Further, since a large current flows to the motor 11, the current transformer 28 supplies considerable current to the field winding 30 through 55

the rectifiers 29. This current may act cumulative or differential to the series field winding 31, depending on the torque characteristics required for motor 12. The voltage of the generator 13 is thus very materially increased and the drill stem is retrieved sufficiently to permit starting of the drill stem, regardless of the length of the stem, or the depth of the well.

As the controller 32 is moved to positions *b*, 10 *c* and *d*, respectively, the resistor sections 46, 45 and 44 are successively shunted and for normal drill operation, the induction motor 11 operates as a squirrel cage induction motor.

As the character of the strata being drilled 15 varies from time to time, the load on the drill motor either increases or decreases, and in consequence, more or less current is supplied to the field winding 30. If the load increases, as is usually the case when a comparatively soft strata 20 is being drilled, the excitation of the field winding 30 is materially increased and the voltage of the generator 13 is thus considerably increased. The torque motor 12, having substantially constant excitation, will thus retrieve the drill stem 25 sufficiently to maintain a substantially constant torque on the drill motor 11. If, on the other hand, the torque on the drill stem decreases, the effect of field winding 30 decreases and in consequence, the weight of the drill stem 2, resting 30 on the strata being drilled, is increased, so that again the torque on motor 11 is maintained substantially constant. For each length of the drill stem, and depending upon the size of the drill motor as well as the size of the hoisting motor, the rheostat 55 35 may need to be adjusted for the initial operating torque. After the adjustment for a given length of drill stem has been made, no further adjustments need be made, because the current transformer operating through the 40 rectifiers 29 suitably controls the voltage of the generator 13 to either retrieve the drill stem or permit the drill stem to descend. This system will thus regulate for both torque on the drill motor as well as for the weight of the drill stem. Further, with this arrangement the feed motor 45 will only need to be of such size as is necessary to retrieve the drill at a satisfactory rate of speed for suitable control, since current will be furnished to the armature of the hoist motor by the small motor generator set, represented 50 by the machines 14 and 13, the voltage of the generator of which is automatically being adjusted to give the proper torque for the motor 12. The motor 12 will thus at all times be responsive to the torque of the drilling motor driving 55 the rotary table 1.

It will be seen that any change in load on the drilling motor will cause a corresponding change in the current and field excitation of the variable voltage generator 13 and, therefore, a change in voltage impressed upon the armature of the feed motor which will vary its torque so as to maintain substantially constant torque on the drill motor, and constant weight on the drill 65 stem.

The switch 27 is provided for the purpose of shunting the resistor 26, whereby the motor 12 is provided with a strong field excitation so that if the drill stem for any reason has gotten stuck, 70 it will, by the jolt of the hoist motor 12, free the drill stem from a material gripping it in the well.

It is to be understood that the control system herein disclosed is merely illustrative of my very simple and inexpensive system of control, and

that other systems falling within the spirit of this invention and within the scope of the appended claims may readily be devised by those skilled in the art, after having had the benefit of the teachings of this invention, but I wish only to be limited by the claims hereto appended and the pertinent prior art.

I claim as my invention:

1. In a well-drilling system for a rotary rig, in combination, a drill table, a motor for driving the table, a drill stem operated by the table, a hoist-drum for lowering and hoisting or retrieving the drill stem, a motor for operating the hoist-drum in either direction, a generator for energizing the motor, and means responsive to the torque on the drill motor for varying the voltage of the generator energizing the hoist motor.

2. In a rotary well-drilling system, in combination, a drill stem, a drill table for operating the stem, a motor for driving the table, a hoist-drum for lowering and retrieving the stem, a torque motor for operating the hoist-drum, a generator for supplying energy to the torque motor, means for varying the voltage of said generator proportionally to the variations in torque of the motor operating the drill table, whereby the stem is retrieved and lowered by an amount sufficient to maintain substantially constant torque on the motor operating the drill table.

3. In a rotary well drilling system, in combination, a drill stem, a drill table, an induction motor for driving the drill table, a hoist-drum, a hoist motor for operating the hoist-drum, a motor-generator set for energizing said hoist motor, means responsive to the torque of the induction motor for controlling the operating characteristics of the motor-generator set so that the energy supplied to the hoist motor keeps a constant torque on the drill motor.

4. In a rotary well-drilling system, in combination, a drill stem, a drill table for operating the stem, a drill motor for operating the table, a hoist motor for controlling the weight of the drill stem on the bottom of the well, a motor-generator set for energizing the hoist motor, means responsive to the load current of the drill motor for varying the operating characteristics of the motor-generator set to thus maintain the weight of the drill stem on the bottom of the well substantially constant.

5. In a well-drilling system, in combination, a motor for operating the drilling tool, a hoist drum and hoist motor for operating the drum, a motor-generator set for energizing the hoist motor, and means responsive to the torque of the motor for operating the drilling tool to control the operating characteristics of said motor-generator set to maintain the torque on the motor operating the drilling tool constant.

6. In a rotary well-drilling system, in combination, a drill stem, a drill table for operating the stem, a drill motor for operating the drill table, a hoist-drum, a constantly excited torque motor operating said drum to vary the vertical position of said stem, a generator connected in series circuit relation with the torque motor, a motor for driving the generator at substantially constant speed, excitation control means for the generator, said means including a device responsive to the load current of the drill motor whereby the voltage of the generator is controlled to be directly proportional to said load current and the torque on the drill motor is thus maintained constant.

7. In a well drilling system, in combination, a drill table, a motor for operating the tool, a hoist-

drum, a hoist motor for operating the drum; means for varying the torque of the hoist motor by a substantially predetermined amount, and means responsive to the load current of the motor 5 operating the drilling tool for gradually varying the torque of the hoist motor to maintain the load on the motor operating the drilling tool substantially constant.

8. In a rotary drilling system, in combination, 10 a drill stem, an alternating current motor for driving the stem, a current transformer having primary and secondary windings connected to be

energized proportional to the load current of the motor, a rectifier interconnected with the secondary winding of the transformer, a generator having a field winding, said field winding being supplied with energy from said rectifier whereby the voltage of the generator is directly proportional to the load current of the alternating current motor, a constant-excited motor interconnected with said generator, and a hoist-drum for the drill stem driven by said constant-excited 10 motor.
